210,903

LIGHT DIFFUSER FOR LUMINAIRES

John Dalton, Jr., Wheeling, W. Va., assignor to Sylvania
Electric Products Inc., a corporation of Delaware

Filed Dec. 8, 1965, Ser. No. 113

Term of patent 14 years

(Cl. D48—16)

FIG.1

FIG.2

FIG.3

FIG.4

FIG.5

FIGURE 1 is a bottom view of a light diffuser for luminaires showing my new design.

FIGURE 2 is a sectional view taken along the line 2—2 of FIG. 1.

FIGURE 3 is a fragmentary bottom view on an enlarged scale of the light diffuser of FIG. 1.

FIGURE 4 is a fragmentary cross sectional view on an enlarged scale of the light diffuser of FIG. 1.

FIGURE 5 is a bottom perspective view of the light diffuser of FIG. 1.

I claim:

The ornamental design for a light diffuser for luminaires, as shown.
